UNITED STATES PATENT OFFICE.

GEORGE A. GRAEF, OF SOUTH PLYMOUTH, NEW YORK.

SILO-DOOR.

1,368,137.

Specification of Letters Patent.

Patented Feb. 8, 1921.

Application filed December 4, 1919. Serial No. 342,411.

To all whom it may concern:

Be it known that I, GEORGE A. GRAEF, a citizen of the United States, residing at South Plymouth, in the county of Chenango, 5 State of New York, have invented certain new and useful Improvements in Silo-Doors; and I do hereby declare the following to be a full, clear, and exact description of the invention, such as will enable others 10 skilled in the art to which it appertains to make and use the same.

This invention relates to combined securing and ladder attachments for silo doors, it being the object of the invention to provide 15 an attachment to be carried wholly by the silo door but which when utilized as a ladder rung, will tend to draw the door outwardly and thus seat it more securely in the door opening, as distinguished from tending to 20 dislodge the door into the silo, so that there will be no danger to the user incident to slipping of the silo door from place due to the weight of the user as he mounts the ladder that is formed by the succession of attach- 25 ments on the succession of door sections.

A further object of the invention is to provide a construction which will serve to prevent accidental falling of the door section into the silo when the door is being put in 30 place or is being removed.

Other objects and advantages will be apparent from the following description when taken in connection with the accompanying drawing.

35 In the drawing:

Figure 1 is an elevation of a portion of a silo showing the improved door in place.

Fig. 2 is a vertical sectional view taken on the line 2—2 of Fig. 1, through the door and 40 retaining or supporting means.

Referring particularly to the accompanying drawing, 10 represents the wall of the silo, and 11 the opening through which silage is introduced into the silo, and in which is 45 disposed the door 12. This door has its upper and lower edges beveled—for providing a leak proof joint with the adjacent doors above and below it. The side edges of the door, as well as the vertical sides of 50 the opening are correspondingly beveled.

Secured to the outer face of the door, and projecting outwardly, are the brackets 13. To each bracket is pivotally connected one arm of a yoke 14, the transverse portion of

which is adapted to serve as one rung of a 55 ladder, of which the corresponding members of the other doors of the silo form the remaining rungs. This enables a person to climb to any height on the silo for the purpose of removing the doors when the ensilage 60 is to be removed. Secured to the lower ends of the arms of the yoke is a transverse bar 15, the ends of which extend beyond the sides of the opening of the silo and bear against the outer face of the wall.

65 The transverse portion of each yoke serves as a handle by means of which the yoke is rocked so that the door may be lifted out of the opening.

Upon reference to the drawings it will be 70 noted that when a person stands upon the cross member of the yoke, the end portions of the cross bar 15 are forced against the outer face of the silo at both sides of the door opening and that the beveled door section 75 12 tends to draw outwardly into closer relation to the corresponding bevels of the sides of the door opening and the upper edge of the door section next below. Thus, the door section that bears the weight of a person 80 cannot slip inwardly from place with corresponding danger to the person in question. The same remarks apply to the upper attachment that may be grasped by a person in climbing the silo.

85 Again, in putting a door section in place, it sometimes slips and drops into the silo, causing much annoyance and loss of time. With the extensions of the cross bar 15, the dropping of the door section into the silo is, 90 of course, prevented and furthermore after one door section has been secured in its final position, another door section may be hung within the silo, ready to be given its then slight adjustment into its closing position.

95 What is claimed is:

The combination with a silo having a door opening and a door section adapted to be drawn into the door opening from within the silo and means for preventing outward 100 movement of the door section directly from its closing position, of a yoke comprising parallel arms and a ladder rung forming transverse portion connecting their upper end, said arms being pivotally connected intermediate of their ends with the outer face of the door section and extending downwardly from their said connecting member,

and a cross bar connecting the free ends of the arms and extending transversely of the outer face of the door section and materially across the outer face of the silo at both sides 5 of its door opening, whereby to deliver pressure to the silo wall, and to prevent dropping of the door into the silo when released.

In testimony whereof, I affix my signature, in the presence of two witnesses.

GEORGE A. GRAEF.
